UNITED STATES PATENT OFFICE.

CHARLES FREDERICK NAEGELE, OF NEW YORK, N. Y.

DESIGN FOR A MEDAL.

SPECIFICATION forming part of Design No. 22,240, dated February 28, 1893.

Application filed January 11, 1893. Serial No. 458,090. Term of patent 7 years.

To all whom it may concern:

Be it known that I, CHARLES FREDERICK NAEGELE, a citizen of the United States, and a resident of the city of New York, in the county of New York, have invented a new and original Design for Medals, &c., of which the following is a specification.

My invention relates to medals &c., and consists of a design for such medals. My design is represented in the accompanying drawings, in which Figure 1 is a face view and Fig. 2 a vertical section.

My design consists of a central figure A and a figured margin B. The central figure A represents the head of Christopher Columbus. The figured margin B contains a representation of vessels and fish-like forms.

Outside of these figures are several wavy lines. The vessels are arranged with their hulls nearest to these wavy lines and their masts extending from the hulls inward toward the center of the design.

What I claim, and desire to secure by Letters Patent, is—

The design for medals &c. consisting of an antique head in the central portion and three approximately equidistant vessels, and wavy lines in the surrounding portions, substantially as shown and described.

CHARLES FREDERICK NAEGELE.
